UNITED STATES PATENT OFFICE.

FRANK H. NEWCOMB, OF ASHLAND, MASSACHUSETTS.

WHISTLING-PROPELLER TOY.

Application filed July 8, 1924. Serial No. 724,838.

To all whom it may concern:

Be it known that FRANK H. NEWCOMB, a citizen of the United States of America, residing at Ashland, in the county of Middlesex and State of Massachusetts, has invented new and useful Improvements in Whistling-Propeller Toys, of which the following is a specification.

The present invention has for its purpose 10 to provide, in a toy of this kind, a propeller construction with the lobes or blades oppositely pitched so that, when a twisting cord (on which the propeller is operatively mounted) is pulled first in one direction and then the other, the propeller will act to displace the air first in one direction and then the other.

Another purpose is to provide a whistling propeller toy, the lobes or blades of which 20 are hollow and provided with opposite axially aligned openings, the walls of the hollow lobes or blades being arcuate as shown, so that when the propeller toy is revolving first in one direction and then the other, the 25 hollow lobes or blades will draw in and expel the air and thereby create a whistling noise.

Still another purpose is to provide a toy of this kind which will create considerable 30 amusement for children and since the lobes or blades are tinted in various colors, the whirling propeller will create an attractive and pretty aspect, especially in the sunlight.

A further purpose is to provide a propeller toy of this kind which may be manufactured at a relatively small cost and sold at a reasonable profit, said toy having opposite hub pieces through which the twisting cord or the like engages, opposite portions of the 40 cord engaging through spaced openings of the hub pieces so as to create a twisting action of the cord when the ends of the cord are pulled in one direction and then relaxed.

It is to be understood that the particulars herein given are in no way limitative and that, while still keeping within the scope of the invention, any desired modifications of detail and desired proportions may be made in the device according to the circumstances.

The invention comprises further features and combinations of parts to be hereinafter set forth, shown in the drawings and claimed.

In the drawings:

55 Figure 1 is a view showing a propeller toy constructed in accordance with the in-

vention and mounted on a twisting cord, the loop ends of the cord being shown in engagement with the fingers of an operator, and also illustrating the lobes or blades as provided with whistle constructions.

Figure 2 is an enlarged detail view of the propeller toy removed from the cord, showing one of the lobes or blades in section.

Referring to the drawings, 1 designates a propeller hub which has oppositely disposed radial propeller lobes or blades 2. These lobes or blades may be any suitable length and shape, preferably as illustrated, 70 and are oppositely pitched so that, when the propeller toy is whirling, rotating first in one direction and then the other, it will displace the air first in one direction and then the other.

Each blade or lobe is hollow, as shown at 3, and the opposed walls 4 thereof are arcuate. The opposed walls have axially aligned circular openings 5 and due to the whirling movement of the propeller toy, the 80 openings, due to the spacing and proper curving of the walls, draw in and expel the air as the propeller toy whirls, thereby creating a whistling noise.

Passing through and secured to the hub 85 1 are the opposite portions 7 of an endless loop of cord, twine or similar material. The opposite portions of the loop are engaged by the fingers of an operator and then the propeller toy is first partially rotated by hand so as to partially twist the opposite portions of the cord on opposite sides of the propeller toy. After so starting the propeller toy and partially twisting the cord, the operator may then apply pulling 90 action in opposite directions from the propeller toy and then relax the pull which will cause the opposite portions of the cord to twist and untwist and thereby cause the propeller toy to receive rapid revoluble movements. The propeller will act to displace the air first in one direction and then the other and due to the drawing in and expelling of the air through the opposite openings 5 during the rotation of the propeller 95 toy, a whistling noise is created.

The invention having been set forth, what is claimed is:

1. As an article of manufacture, a whistling propeller toy comprising a hub provided with radial blades oppositely pitched whereby the propeller, upon receiving rev-

3
oluble movements first in one direction and then the other, expels the air first in one direction and then the other at right angles to the direction of rotation of the propeller, 5 and an operating twisting cord on which the propeller toy is operatively mounted and whereby, upon exerting pressure in directions away from the propeller longitudinally of the cord and alternately relieving the 10 pressure, revoluble movements are imparted to the propeller, the opposite walls of the propeller blades being arcuate and provided with axially aligned circular openings which act to draw in and expel the air during the 15 rotation of the propeller for the purpose of creating a whistling noise.

2. As an article of manufacture, a propeller toy comprising a propeller hub provided with opposite radial blades which are hol-

20 low and oppositely pitched, whereby a rev- oluble action of the propeller will displace the air first in one direction and then the other, and an operating twisting cord in an 25 endless loop with its opposite portions passing through the hub of the propeller where- by, upon exerting pressure in direction away from the propeller and then relieving the pressure, the propeller receives revoluble movements, the opposite walls of the hollow blades being substantially spaced cen- trally thereof and provided with axially aligned openings in the centers of the walls 30 whereby, upon the propeller receiving revoluble movements, air is drawn in and ex- pelled, thereby creating a whistling noise. 35

In testimony whereof he affixes his signature.

FRANK H. NEWCOMB.
